UNITED STATES PATENT OFFICE.

JOHN F. REARDON, OF FALL RIVER, MASSACHUSETTS, AND EMMERICH H. KRISTEK,
OF THOMPSON, CONNECTICUT.

TENSION DEVICE.

1,330,006.

Specification of Letters Patent.

Patented Feb. 3, 1920.

Application filed January 4, 1918. Serial No. 210,331.

To all whom it may concern:

Be it known that we, JOHN F. REARDON, a citizen of the United States, residing at Fall River, in the county of Bristol and State of Massachusetts, and EMMERICH H. KRISTEK, a citizen of the United States, residing at Thompson, in the county of Windham and State of Connecticut, have invented certain new and useful Improvements in Tension Devices, of which the following is a specification.

This invention relates to improvements in tension devices for use in connection with bobbins, cops, roquets and the like and it is the principal object of the invention to provide a device whereby the thread or other strands of material will be placed under sufficient tension during the loading or doffing of the bobbin, etc., to prevent tangling and the resultant rupturing of the thread.

It is a more specific object of the invention to provide a tension device of the character mentioned formed of low frictional material and having an even bearing surface whereby the thread, yarn or the like will be allowed to move freely thereover without liability of rupture.

Among other aims and objects of the invention may be recited, the provision of a device of the character mentioned with a view to compactness, and in which the number of parts are few, the construction simple, the cost of production small, and efficiency and operation high.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

In the drawings:—

Figure 1 is an elevation of the improved holder,

Fig. 2 is a similar view of the same taken at right angles to the Fig. 1, and

Fig. 3 is a vertical section through the tension means and a portion of the bracket.

Similar reference characters refer to similar parts throughout the several views of the drawings.

Having more particular reference to the drawings, 1 represents the supporting bracket in its entirety, the lower portion of

which is off-set to provide a base portion 2, while the upper end of the same is off-set as at 3 to provide a supporting arm, the free end of which is apertured and receives therethrough one end of a bolt 4 the purpose of which will be subsequently described; it being noted in this connection, that the said bolt is secured rigidly to the arm 3 by means of locking nuts 5.

An upright bearing pintle 6 is arranged upon the off-set base portion 2 and rotatably supports a bobbin 7, or a spool or other suitable device. To permit the bracket 1 to be secured to a suitable support, laterally extending arms 8 are formed upon the intermediate portion of the same, one of the said arms being apertured and receiving a locking or clamping set-screw 9 therethrough; the said screw obviously, being turned into engagement with the device to which the bracket is attached.

Disk like members 10 and 11 having concentrically disposed openings are supported on the bolt 4 and receive therebetween a tension device 12 formed of glass or other suitable low frictional material and having a concaved peripheral surface free of seams or the like. To insure proper engagement of the disk like members 10 and 11 with the tension device 12, the adjacent portions of the same are provided with annular flanges and receive therein gaskets 13 formed of felt or other similar material, which gaskets, as will be noted, receive the adjacent marginal portions of the said tension device thereon, thereby preventing rattling or other undue movement of the same. Further, a spring thrust member 14 is arranged upon the outer end of the bolt 4 and is engaged with the adjacent side of the disk like member 10 through the medium of a locking nut 15.

Guide hooks 16 and 17 are formed integral with the peripheral portions of the disk like bodies 10 and 11; the element 16 being of a length slightly greater than the element 17. The thread, yarn or other strand of material is passed upwardly from the bobbin or like device supported on the bearing pintle through the guide element 16 then about the tension device and thence through the hook 17 or guide elements 17 to the device feeding or receiving the same. Obviously, in this way, proper movement of the thread with relation to the bobbin is caused.

From the foregoing, it will be readily un-

derstood by workers skilled in the art that we have provided an exceedingly simple and efficient tension device which may be adapted for use in connection with practically any form of reeling or unreeling device, such as bobbins, cops, cheeses, spools, roquets, etc., whereby the rupturing of the strand wound thereonto or therefrom will be prevented. Furthermore, by forming the tension device of low frictional material, the splitting or tearing of the thread, yarn or other material engaged therewith is positively prevented.

Manifestly, the construction shown is capable of considerable modification and such modification as is within the scope of our claim we consider within the spirit of our invention.

We claim:—

10 A holder of the character described including a standard, a frangible cylindrical tensioning device provided with a concave

peripheral surface, clamping members arranged at the opposite ends of the tension device, circular inwardly directed flanges receiving the terminal portions of the tension device, a bolt passing axially through the clamping members, means rigidly connecting one of the clamping members with the standard, the other clamping member being movably mounted upon the bolt, cushioning elements confined within the flanges of the clamping members and interposed between the latter and the tension device, and means carried by the bolt and engaging the relatively movable clamping member to normally retain the latter in engagement with the tension device.

15 In testimony whereof we affix our signatures hereto.

JOHN F. REARDON.
EMMERICH H. KRISTEK.
